METHOD OF BURNING OIL AS GAS

Charles B. Hillhouse, New York, N. Y.

Application July 10, 1933, Serial No. 679,767

13 Claims. (Cl. 158—117.5)

My invention relates to a method of burning oil. Additional means are provided to maintain the gasified oil in a heated state until the gasified oil and gases of combustion of oil wherein a portion of the fuel to be burned, preferably oil or other hydrocarbon, is caused to combust in a manner to produce hot combustible gases which are mixed at a suitable temperature with a larger portion of fuel to gasify it and these mixed gases may be burned with sufficient air at some distance from the zone of gasification to produce the main zone of combustion. My invention relates to a method of burning oil in a heated state by indirect heat application to produce combustible gas, and then mixing the hot products of partial combustion and gas mixed therewith intimately with another portion of fuel to gasify the latter portion and burning the gaseous mixture with sufficient air, preferably preheated, for complete combustion in a main combustion chamber. Another object is that of gasifying the main portion of oil and maintaining that gasified oil in a suitably heated state while mixed with the gases formed by the partial combustion of the smaller portion of oil until the mixture is permitted to meet preheated air in the burner or burners.

Another object is to control the temperature of the gases formed by partial combustion so that, when the larger portion of oil is sprayed or mixed with these gases, there will be sufficient sensible heat in the gases to gasify the main portion of oil, but not enough sensible heat to cause any detrimental deposition of carbon at the time or point of mixing, particularly where the burners are situated at a distance from the point of production. The present application and process follows in a general way the process disclosed in my copending application, Serial No. 650,707, filed January 7, 1933, and is a continuation in part thereof, but it carries out the method in a somewhat different manner. In the present application, the smaller portion of oil to be gasified is conducted through a spirally formed metal tube which is positioned to surround the hot gasification zone in a manner to preheat this smaller portion of oil before it is discharged into the zone where this smaller portion of oil is partially combusted. I provide also a means in the form of spirally arranged cooling coils located in a manner to regulate the temperature of the hot gases of partial combustion and, thereby indirectly, the temperature at which the larger portion of oil, or fuel, is gasified. Addi-

tional means are provided to maintain the gasified oil in a heated state until the gasified oil and gases of partial combustion are mixed with sufficient air to be burned in the main fuel burner. This additional means may comprise air that has been preheated by proximity to the partial combustion zone for the purpose of maintaining a reduced temperature thereof; and which air, so preheated, is applied to the burner is short and ample means are applied to prevent material loss of heat from the gas mixture. I may dispense with the use of the heat applied as a surrounding jacket.

In the accompanying drawing, Figure 1 shows an elevation in cross-section of an oil burner constructed to carry out the method described; Figure 2 shows a cross-section on line 2—2 of Fig. 1; and Fig. 3 shows a cross-section on line 3—3 of Fig. 1.

In the preferred form of apparatus shown, a gasification chamber 1 is shown as having an outer heat insulating wall 2 and an inner refractory wall 3 to provide an air conducting space 4. The smaller portion of oil that is to be burned, to produce combustible gas is supplied under a suitable pressure from a conduit 5 into a spray tube 6 by means of an injecting device 7. The tube 6 leads into chamber 1 and the oil spray therefrom is conducted through a spirally arranged pipe 8 into a burner 9 to which it is fed from a nozzle 10. This oil is preheated in spiral pipe 8 which surrounds the partial combustion zone above burner 9. A blower 11 supplies air to a conduit 12 which is connected to a conduit 13 which terminates in an air-feed pipe 14 within burner 9. A valve 15 serves to control air supply to burner 9 in sufficient amount to cause partial combustion; that is, enough air is used to burn all the carbon in that portion of oil to CO, but not enough air to combust the hydrogen nor make any CO₂. Air from pipe 14 draws in heated oil from the spiral 8 at the throat 10 of nozzle 10. If desired,

starting of burner 9 may be facilitated by heating oil in pipe 8 with electric heating coils therein.

Air from conduit 12 enters the space 4 at inlet 16 and passes upwardly around the heated wall 5 3 to become preheated. Air from the blower 11 passes also through a conduit 17 and valve 18 and an inlet 19 into a spirally arranged conduit 20 that surrounds the zone of combustion from burner 9. The air in conduit 20 extracts heat from this 10 zone of combustion in an amount regulated by valve 18 and leaves the conduit 20 by an outlet 21 which communicates with the space 4.

The preheated air in space 4 passes upwardly and is conducted along a path to surround the 15 gas outlet conduit being confined in a space 23 formed between the conduit 22 and a heat insulated wall 24. The gases from chamber 1 pass upwardly through an outlet throat 25 into conduit 22. The larger portion of oil fuel is supplied from 20 a pipe 26 under pressure, if desired, and is sprayed into the throat 25 by means of an air injecting device the air flow through which is controlled by valve 28.

Oil sprayed into throat 25 is gasified and is 25 maintained in a gasified state by application thereto of heated air in the space 23 which air functions as a heated insulating medium, hence this oil gas may be efficiently conducted an appreciable distance from the chamber 1 to a suitable 30 burner 29 or auxiliary burners 29'. Heated air from the space 23 is supplied to the burner through air inlet 30 and the oil gas is supplied through gas inlet 31.

The air passing through spiral conduit 20 serves 35 to draw off excess heat from the gases of partial combustion in chamber 1 before having the larger portion of oil fuel sprayed into these gases at the throat 25 so that the mixture will assume the exact temperature desired. The temperature 40 of the gases and gasified oil admitted to the conduit 22 is so regulated that the mixture will have a temperature of about 600 degrees F. or below a temperature at which there will be any dissociation of carbon to form a deposit.

In the operation of my device, oil from spiral 45 conduit 8 is supplied to nozzle 10 and air in regulated amounts from air inlet 14. This oil and air is partially combusted, that is, the air is in insufficient amount to combust the hydrogen or 50 make any CO₂, although all of the carbon is burned to form CO. The zone of combustion is indicated by dotted lines A—B. Air from conduit 17 is forced through the spiral conduit 20 to be preheated and extract heat from the hot gases of 55 partial combustion. This air is then passed into space 4 and out of the gas generator and into the space 23 to surround the conduit 22. There is little or no interchange of heat between the hot air jacket and the made gases when not over 600 degrees F. difference in temperature exists between them when only a short time has elapsed for transfer of the gas to the burner. The major portion of oil fuel from conduit 26 is sprayed into the throat 25 and is gasified and is maintained in that form due to the stabilizing action of heated air in the space 23 surrounding this gas. This 65 heated air all or in part, in turn, is supplied to the burner 29 to mix with made gases admitted from fuel inlet 31.

The temperature to be aimed at for the mixture of sprayed oil and gases of partial combustion should be about 600 degrees F. so as to be secure from any carbon deposition. To prevent any breakdown of the unstable oil gases before reaching the burner 29, the pipe 22 conveying the above

mixture is encased in another pipe 24 making a double shell. The hot air between these shells is maintained at about 450 degrees F. Due to the relation of made oil gas and heated air and the stabilizing action of the heated air upon the temperature of the oil gas, the oil gas may be conveyed to a burner or burners located at some distance from the gasifier without appreciable change in character of the final mixture of generated oil gases. One of the essential features of 10 this process is to control the temperature of the axial zone of gases of partial combustion A—B so that when the larger portion of oil is sprayed in the gases to gasify the oil but not enough to cause 15 any deposition of carbon. This is brought about by the cooling effect of the air which is passed through the spiral conduit 20.

This gasification does not make a fixed gas but the gas or gases are permanent so long as they 20 are kept at a temperature sufficiently high to prevent their liquification. For instance gasoline is a gas at its temperature of distillation but at atmospheric pressure and normal temperature takes a liquid form. So what I am doing when I 25 apply generated hot combustible gas to a spray of oil, when the resulting or final temperature is about 650 degrees F., is to gasify the oil and not merely vaporize it. Therefore, I propose to keep that latter gas at a temperature above its reversion point, and burn a mixture of true gases in the burners, though it is not necessarily a mixture of fixed gases at atmospheric pressure and normal temperature.

The temperature of the hot gases of partial 35 combustion may be from 900 degrees to 1000 degrees F. at the instant of spraying oil into same, but the temperature of conversion or lowest temperature after production of the mixture of gases will be not over about 650 degrees, whereby there 40 will be no tendency to produce deposition of carbon as might occur at higher temperatures than 650 degrees F.

While the apparatus disclosed is intended to 45 illustrate a preferred form of the apparatus, it is to be understood that variations thereof are contemplated such as will be embraced within the scope of the appended claims.

What I claim is:

1. A method of burning fluid fuel which consists in preheating a portion of oil in a burner and then reducing it to carbon monoxide and hydrogen by partial combustion, spraying into said reduced portion while in a heated state a portion of fluid fuel, applying additional heat to the mixture to maintain the fuel in a gasified state, and then burning this mixture with sufficient air for complete combustion.

2. A method of burning fluid fuel which consists in reducing by partial combustion a portion of oil to form carbon monoxide and hydrogen gases, lowering the temperature of said formed gases, mixing into said gases a portion of liquid fuel to gasify it and then burning this mixture of gases with sufficient air for complete combustion.

3. A method as set forth in claim 2 wherein the mixture of gases is burned at a point remote from the mixing point, and heat is supplied to the mixture to maintain the gases in gaseous form until 70 the point of final combustion is reached.

4. A method of burning fluid fuel which consists in reducing by partial combustion a portion of oil to form carbon monoxide and hydrogen gases, extracting a portion of the sensible heat 75

from said gases, then mixing with said gases a larger portion of fluid fuel to gasify it at a temperature which will not permit deposit of carbon using the extracted heat to maintain the mixture 5 in gaseous form to prevent its reversion to a liquid form and burning said mixture with air for complete combustion.

5. A method of burning oil which consists in reducing by partial combustion a portion of the 10 oil to form a combustible gas, passing a cooling medium in indirect contact with said gas to lower the temperature thereof, mixing another portion of oil into said gas to form additional gas and applying the heated cooling medium as a jacket 15 around the mixture of gases to prevent reversion of any component thereof to liquid form, and burning said mixture with air for complete combustion.

6. A method as set forth in claim 5 wherein the 20 cooling medium is air, and a portion of the heated cooling medium is mixed with the gaseous mixture to produce complete combustion thereof.

7. A method of burning oil which consists in reducing by partial combustion a portion of the 25 oil to form a hot combustible gas, spraying into said gas another portion of the oil to form a mixture of gases, conducting said mixture along a predetermined path to a burner, applying heat to said mixture throughout its movement along 30 said path to maintain the temperature of the mixture of gases above their dew points and below the point at which carbon deposition might take place and burning said mixture with air for complete combustion.

35. 8. A method as set forth in claim 7 wherein the heat applied to maintain the temperature of the mixture is extracted from the hot combustible gas prior to mixing same with the sprayed oil.

9. A method of burning oil which consists in 40 gasifying by partial combustion a portion of the oil in a retort, conducting the heated gasified portion to a burner remote from the retort, spraying into said heated gasified portion another portion of the oil to gasify the latter portion to form additional gas, applying sufficient heat to the mixture of gases prior to the burning thereof to pre- 45

vent any reversion of gas to a liquid form and burning the mixture with air for complete combustion.

10. A method of burning liquid fuel, which consists in preheating a portion of oil in a burner 5 and then reducing it to carbon monoxide and hydrogen by partial combustion without deposit of carbon, then mixing into said reduced portion while in a heated state a portion of liquid fuel to gasify same, and then burning this mixture with 10 sufficient air for complete combustion.

11. A method of burning liquid fuel in a retort which comprises feeding oil to the retort without air and preheating same, then adding air in amount insufficient for complete combustion of 15 the oil and partially burning this oil so as to produce carbon monoxide and hydrogen gases, mixing a portion of liquid fuel with said gases while in a heated state to gasify same and burning the mixture with secondary air sufficient for complete 20 combustion.

12. A method of burning liquid fuel in a retort which comprises feeding oil to the retort without air and preheating same, then adding air in amount insufficient for complete combustion of 25 the oil, burning said oil and air partially without deposit of carbon to produce carbon monoxide and hydrogen, preheating another portion of oil by heat from this partial combustion, mixing a portion of liquid fuel with the heated gaseous products of partial combustion to gasify same and burning the combined gaseous products with additional air sufficient for complete combustion of 30 the final mixture.

13. A method of burning oil in a retort which 35 comprises feeding a portion of oil to the retort without air and preheating said oil, then adding air in amount insufficient for complete combustion of the oil, burning said oil and air partially to produce carbon monoxide and hydrogen gases, 40 mixing another portion of oil with said gases while in a heated state to gasify same, mixing additional air sufficient for complete combustion of the gases with the gaseous mixture and burning the final mixture. 45

CHARLES B. HILLHOUSE.
